UNITED STATES PATENT OFFICE.

GRANT HAMMOND, OF NEW HAVEN, CONNECTICUT, ASSIGNOR OF ONE-THIRD TO
ALVA C. WASHBURN, OF PITTSFIELD, MASSACHUSETTS, AND ONE-THIRD TO
FREDERICK G. CRANE, OF DALTON, MASSACHUSETTS.

FIREARM.

Application filed February 28, 1917, Serial No. 151,460. Renewed April 12, 1923.

To all whom it may concern:

Be it known that I, GRANT HAMMOND, a citizen of the United States, residing at New Haven, in the county of New Haven and State of Connecticut, have invented a new and Improved Firearm, of which the following is a specification.

My invention, while not limited in use to any special type of firearm, relates particularly to that type that is commonly held in the hand and fired while so held, and an object of my invention, among others, is to provide a firearm that shall be simple in construction and operation and efficient and reliable in use.

One form of firearm embodying my invention, and in the construction and use of which the objects herein set out, as well as others, may be attained, is illustrated in the accompanying drawings, in which—

Figure 1 is a view in central vertical section through a firearm embodying my invention.

Figure 2 is a view in side elevation of a portion of my improved firearm looking at the right hand side, with parts broken away to show construction, the breach-bolt being shown in its forward position, and the hammer cocked.

Figure 3 is a view similar to Figure 2, but with different parts broken away, and with the breach-bolt shown in its rearward position.

Figure 4 is a view in vertical cross section through my improved firearm on plane denoted by dotted line 4—4 of Figure 2.

Figure 5 is a detail view in horizontal section through a portion of the handle and receiver and through the hammer mechanism block on plane denoted by the dotted line 5—5 of Figure 4, the hammer being removed.

Figure 6 is a bottom view of the breach-bolt.

Figure 7 is a top view of the receiver.

Figure 8 is a detail front view of the breach-bolt.

Figure 9 is a view in side elevation of a firearm embodying my invention, the barrel being broken off.

Figure 10 is a detail rear view of the upper part of my improved firearm.

Figure 11 is a side view of the hammer mechanism block.

Figure 12 is a top view of the sear bar. 55

While my invention is not limited in its application to any special type of firearm, as it is particularly adapted to use in that type which is commonly held in the hand and fired while so held, I have selected this 60 type for the purpose of illustration herein in connection with which to describe my invention, only such parts of the firearm as are necessary to an understanding of the invention being shown in the drawings. The invention will be readily understood by those skilled in the art from the drawings forming a part of this specification, in such drawings the numeral 8 indicating the handle or frame of my improved firearm, which may 65 be of any ordinary material and constructed in any desired manner and having a chamber 9 for the magazine, and a trigger-guard 10. The handle has an opening 11 in its front edge for a sear bar, and a slot 12 through its 70 upper rear edge for a hammer mechanism block, and a hole 13 through its upper front edge for a receiver lock. Grooves 14 extend along the upper edges of the handle on opposite sides to receive lips formed on the 75 lower edge of the receiver.

The receiver 15 is of a length substantially equal to the distance from the front to the rear edges of the handle, and it has a breech-bolt opening 16 extending from its rear end 80 to a front wall 17 in which a barrel 18 is secured in any suitable manner, interengaging screw threads being shown herein as such securing means. The receiver has retaining lips 19 projecting towards each other 85 at the upper edge of the opening 16, and a slot 20 is formed through the bottom of the breech-bolt 22.

A hammer mechanism block 23 is secured in the slot 12, its forward edge conforming 90 to the general shape and forming part of the rear wall of the magazine chamber 9 in the handle. This block is secured to the handle by pins 24 and 25, the latter comprising the pivot pin for the hammer 26. 100 A hammer recess 27 is formed in the rear end of the block 23, said recess opening to the upper and rear ends of the block, and a sear chamber 28 and a hammer spring chamber 29 extend inwardly from said recess. 105

A slot 30 is formed in the lower part of the hammer, said slot having a shoulder 31 for the reception of the end of a hammer

- operating plunger 32 that is located in the chamber 29, the end of said plunger being preferably flattened to enter said slot 30. Said plunger is recessed at its forward end 5 to receive one end of a hammer operating spring 33, the other end of said spring resting against the bottom of the chamber 29, that in the construction herein shown, comprises a plug 34 screwed into the front edge 10 of the block 23, and as shown in Figure 1 of the drawings.
- A sear 35 is located in the chamber 28 and is seated upon a sear spring 36. The outer or rear end of this sear has a head 37 formed 15 to engage a notch or notches in the lower edge of the hammer and on opposite sides of the slot 30, said notches being disposed in any ordinary manner. The end of this head is preferably beveled from the top side down- 20 wardly and forwardly as shown in Figure 1 of the drawings, and it is located in an enlarged part 38 forming a mouth at the entrance to the sear chamber 28, the latter chamber being preferably beveled off to receive 25 the beveled part 39 of the sear located back of the head 37.
- A returning spring tensioning lug 40 is secured to the upper side of the hammer mechanism block 23, this lug being of hook 30 shape forming a breech-bolt retaining recess 41 with a beveled surface 42 to engage the beveled surface 43 of a slot in the upper back end of the head 44 of a compression rod 45. The hammer 26 has a recess 46 to 35 receive the spring tensioning lug when the hammer is down, and said spring tensioning lug is secured between breech-bolt camming lugs 47 secured to the upper side of the block 23.
- 40 The breech-bolt 22 is mounted for reciprocating movement in the breech-bolt opening or chamber in the receiver. Retaining shoulders 48 extend lengthwise along opposite sides of the bolt near its upper edge, 45 these shoulders inclining downwardly from the front end toward the back, and as shown in Figure 3 of the drawings. Guide slots 49 are formed in opposite sides of the breech-bolt extending substantially parallel 50 with the shoulders 48, and holding recesses 50 are formed at the rear ends of each of said slots. Guide and stop pins 51 extend from opposite walls of the breech-bolt chamber or opening in the receiver into the slots 55 49, these pins being preferably screw-threaded into the receiver as shown in Figure 4 of the drawings. Retaining lugs 52 are located on the bottom of the breech-bolt in position to engage breech-bolt retaining shoulders 53 60 in the bottom of the receiver, these shoulders, in the construction shown herein, comprising the back edges of a slot 54 formed through the bottom of the receiver. The slot 20 is formed lengthwise in the bottom 65 of the breech-bolt to receive the tensioning

lug 40, and a slot 56 on the bottom of the receiver is of a width to receive the breech-bolt camming lugs 47 that are provided with cam surfaces 57 on their upper edges.

The compression rod 45 is located in a compression rod chamber 58 in the breech-bolt and also contains a breech-bolt returning spring 59, and said rod will project through an ejector opening 60 extending from said chamber through the front end of the breech-bolt when said bolt is at the rearward limit of its play, the rod at this time comprising an ejector to force a cartridge shell from the front end of the bolt in a manner that will be readily understood. An extractor 61 of any desired construction is located on the breech-bolt to coact with the said ejector, and a firing pin 62 of any suitable form and construction extends through the breech-bolt, its rear end being in position 85 to be struck by the hammer 26. In the form shown herein a firing pin spring 63 is located in the enlarged part of the firing pin opening, thrusting with one end against the bottom of said opening and with the other end against a shoulder formed by the enlarged part of the pin, a threaded bushing 64 holding the pin in place and said bushing being held against turning movement by means of a pin extending crosswise through 95 the bolt, as shown in Figure 1 of the drawings.

Grooves 65 extend lengthwise along the under surface of the breech-bolt to receive the upper ends of the side parts of a magazine 66, a rounded projection 67 between said grooves constituting a pusher that contacts with cartridges 68 in the magazine on the forward movement of the breech-bolt and pushes said cartridges into the cartridge 105 chamber in the breech of the barrel 18.

A trigger 69 is pivotally attached to the handle with its rear edge located in a trigger recess 70. A sear bar 71 is pivotally attached to the trigger, and it has a foot 72 110 against which a sear bar spring 73 presses with one end, the opposite end of said spring extending into a recess 74 in the handle. The sear bar is curved at a short distance from its pivot to extend around the magazine, said bar extending through the opening 11 in the handle and having a spring shoulder 75 near its opposite end and on its bottom edge to engage a beveled lug 76 projecting from one face of a sear lever 77 120 pivotally mounted on the wall of a recess 78 in the side of the handle 8. The opposite end of said lever loosely receives the end of a sear stud 79 projecting from the side of the sear 35 and through a slot in the side of the block 23, and also through a slot in the side of the receiver. A controlling pin 80 extends through a hole in the handle 8 from the recess 78 into one of the slots 54 and in position to rest against the under 130

side of one of the retaining lugs 52. This pin controls the action of the sear bar, holding its spring shoulder in engagement with the lug 76 when the breech-bolt is in its 5 forward position but allowing the rear end of said bar to rise under the influence of the spring 73 and thus permitting the shoulder 75 to pass over the lug when the breech-bolt is in its rearward position, the retaining lugs 52 at this time being moved backwardly beyond said pin. The pressure upon the trigger 69, in the operation of firing the gun, is liable to be retained until the breech-bolt has traveled backward and forward in 10 the firing operation of the gun, and should the shoulder 75 remain in engagement with the lug 76 during this backward and forward movement of the breech-bolt, a second and unintentional discharge of the firearm 15 immediately takes place. The disengagement of the shoulder 75 from the lug 76, when pressure on the trigger is retained, and as above described, prevents such "repeat" or unintentional discharge of the fire- 20 arm, the engaging and disengaging action of the sear bar 71 being thus controlled by the movements of the breech-bolt. When the breech-bolt moves forward the beveled forward edge of the locking or retaining lug 25 52 engages the upper end of the pin 80 and forces it downwardly, causing downward movement of the rear end of the sear bar, this movement of the sear bar being permitted by engagement of the spring shoulder 30 35 40 45 50 55 60 65 70 75 80 85 90 95 100 105 110 115 120 125 130 135 140 145 150 155 160 51 with the holding recesses 50 at the rear ends of the guide slots 49, the location of said pins in said recesses holding the breech-bolt at the forward limit of its movement within 5 the receiver until the pins 51 are disengaged from the recesses by lifting of the breech-bolt caused by the cams 57. When the backward movement of the breech-bolt has been completed the returning spring 59 10 will act to move it forward and after the locking lugs 52 have passed the camming lugs 47 the breech-bolt will drop and locate the locking lugs within the slots 54 in the receiver and thus lock the breech-bolt in its 15 closed position. At this time the spring 59 will force the head of the compression rod into the retaining recess 41 thus engaging the beveled surfaces of the recess and head, which engagement holds the breech-bolt in 20 its locked position with a force depending upon the amount of tension in the returning spring 59.

When the receiver moves back upon the handle the spring in the hole 13 forces the 25 lock 82 into the check recess 84, the rear end of which recess is beveled to an extent to retain the parts in this position. This bevel, however, is such that when the breech-bolt in its forward movement strikes 30 the front wall 17 the force of the impact will disengage the lock 82 from the recess 84 and the receiver, barrel and breech-bolt will be moved forward on the handle to the position shown in Figure 1. During this 35 forward movement of the breech-bolt a cartridge will be forced from the magazine into the breech in the barrel in a manner well known.

In accordance with the provisions of the 40 patent statutes, I have described the principle of operation of my invention, together with the device which I now consider to represent the best embodiment thereof; but I desire to have it understood that the device 45 shown is only illustrative, and that the invention can be carried out by other means.

I claim—

1. A firearm including a handle, a receiver slidably mounted on the handle and 50 having a slot therein, a lock located in a hole in the handle and projecting into said slot, a lock operating member secured to said lock and located within the opening in the trigger guard of the firearm, and means for disengaging the receiver and said lock by impact of the breech bolt at the time it strikes the receiver.

2. A firearm including a handle, a receiver slidably mounted on the handle and 60 having a slot, a check recess opening out of said slot at one end thereof, a lock mounted on the handle and projecting into said recess, means for forcing the lock into said check recess, means for operating the lock, 65 and means for disengaging the receiver and

said lock by impact of the breech bolt at the time it strikes the receiver.

3. A firearm including a handle, a receiver slidably mounted therein and having a slot, a check recess opening out of said slot at the front end thereof, a spring underlying said lock to force it into said recess, a rod projecting from the lock and having a knob at its outer end located within the opening in the trigger guard of the 75 firearm, and means for disengaging the receiver and said lock by impact of the breech bolt at the time it strikes the receiver.

4. A sear mechanism including a movable member, a sear bar with a shoulder at its 80 rear end to engage said member, means acting independently of the rearward movement of the sear bar for raising its rear end to disengage said shoulder, means for forcing the rear end of the bar downwardly to re- 85 engage said shoulder, and a trigger operatively connected with said bar.

5. A sear mechanism including a movable member, a sear bar having a shoulder at its rear end to engage said member, a trigger pivotally attached to said bar, a foot 90 extending from the bar, a spring engaging said foot to raise the rear end of the bar, and means to reengage the bar with the said movable member.

6. A sear mechanism including a movable member, a sear bar having a shoulder to engage said member, a trigger having a slot, a foot projecting from the bar within said slot, said trigger and bar being pivotally 100 united, a spring pressing with one end against said foot to raise the rear end of said bar, and means for forcing the rear end of the bar down.

7. A sear mechanism including a movable member, a bar having a shoulder to engage said member, a foot projecting from the forward end of the bar, a trigger having its rear edge located in a recess in the handle of the firearm, said trigger having a slot, the 110 foot of said bar projecting into said slot, a spring projecting from the recess in the handle and pressing against said foot, and means for pressing the rear end of said bar downwardly.

8. A firearm including a trigger and a breech-bolt, sear mechanism including a movable member, a sear bar connected with the trigger and having a shoulder to engage said member, means for disengaging the shoulder from said member, and a member co-operating with said bar and positioned to be operated by the breech-bolt in its movement to reengage said bar and said movable member.

9. A firearm including a trigger and a breech-bolt, sear mechanism including a movable member, a sear bar operatively connected with the trigger and having a shoulder to engage said movable member, and a 130

pin slidably mounted with one end in engagement with the sear bar, and the other in the path of movement of a projection from the breech-bolt.

- 5 10. A firearm including a trigger and a breech-bolt, sear mechanism including a movable member, a sear bar operatively connected with the trigger and having a shoulder to engage said movable member, and a 70
10 pin projecting through the frame of the firearm and resting against said bar, one end of said pin being located in the path of movement of a locking lug on the bottom of said breech-bolt.
- 15 11. A firearm including a frame, a receiver slidably mounted on the frame, a breech-bolt slidably mounted on the receiver and having a guide slot diagonally arranged with respect to a horizontal plane passing 75
20 through the axis of the breech-bolt when the firearm is in its upright position, a pin projecting from the receiver into said slot to guide the breech-bolt in its movement and to limit its backward movement, a locking lug 80
25 on the bottom of the breech-bolt entering a hole in the receiver, and means to engage the breech-bolt during backward movement of the receiver on the frame to lift said lug out of said hole.
- 30 12. A firearm including a frame, a receiver slidably mounted on the frame, a breech-bolt slidably mounted on the receiver, a locking lug on the bottom of the breech-bolt entering a hole in the receiver, a headed 85
35 compression rod located within a hole in the breech-bolt, the latter having a slot, a tensioning lug projecting from the frame in line with said slot and having a recess to receive said head, means to engage the 90
40 breech-bolt to lift it and disengage said lug from said hole, and means for stopping the backward movement of the breech-bolt.
13. A firearm including a frame, a receiver slidably mounted on the frame, a breech-bolt slidably mounted on the receiver, a locking lug on the bottom of the breech-bolt engaging a hole in the receiver, a headed compression rod located within a hole in the breech-bolt, the latter having a slot opening 95
45 into said hole, a spring pressing against said rod, a camming lug projecting from the frame to engage the locking lug on the breech-bolt and raise the latter to disengage 100
50 said lug from said hole, a tensioning lug secured to said camming lug and registering with said slot, and having a recess to receive the head on the compression rod, and means for stopping the backward movement 105
55 of the breech-bolt.
- 55 14. A firearm including a frame, a receiver slidably mounted on the frame, a breech-bolt slidably mounted on the receiver, locking lugs on the bottom of the breech-bolt engaging shoulders on the bottom of 110
60 the receiver, said bolt having a chamber and a slot opening thereout, a spring in said chamber, a compression rod seated against said spring and having a beveled end, a tensioning lug projecting from the frame opposite the slot in the bolt and having a beveled recess to engage the beveled surface on said rod, and means for stopping the rearward movement of the breech-bolt. 70
15. A firearm including a frame, a receiver slidably mounted on the frame, a breech-bolt slidably mounted on the receiver, locking lugs projecting from the bottom of the breech-bolt into a hole in the receiver, said bolt having a chamber with a slot opening thereout, camming lugs located on the frame to pass along a slot opening into said hole in the receiver, a tensioning lug projecting from the frame and registering with said slot in the breech-bolt, a compression rod having a head located in the chamber in 80
85 the breech-bolt and in engagement with said tensioning lug, and means for limiting the backward movement of the breech-bolt.
16. A firearm including a frame, a breech bolt slidably supported by the frame, means for locking the breech-bolt against movement, means for disengaging said lock, said bolt having a chamber with a slot opening thereout, a compression rod located in said chamber and having a beveled head, and a tensioning lug projecting from the frame opposite said slot and having a beveled recess to engage said head. 90
17. A firearm including a frame, a breech-bolt slidably supported by the frame, means for locking the breech-bolt against movement, means for disengaging said lock, said bolt having a chamber with a slot opening thereout, a compression rod seated against a spring in said chamber, a tensioning lug secured to the frame to engage said compression rod, a hammer pivotally mounted in the frame and having a recess to receive said tensioning lug, and means for operating the hammer. 100
105
18. A firearm including a handle, a receiver slidably mounted thereon and having a slot and a barrel opening extending into said slot, a barrel located in said opening and having a locking recess registering with said slot, and a lock located on the frame to project through said slot into said recess in the barrel. 110
115
19. A firearm including a frame, a receiver movably mounted on the frame and removable therefrom, a breech-bolt movably mounted in the receiver, means to prevent disengagement of the receiver from the frame while permitting a limited movement thereon, said means being also arranged to engage the receiver and hold it temporarily in its rearward position, and firing mechanism to cause action of the breech-bolt. 120
125
20. A firearm including a frame, a receiver movably mounted on a frame, 130

a barrel rigidly secured to the receiver, a breech-bolt movably mounted in the receiver, means to lock the breech-bolt and receiver together for simultaneous movement 5 and to unlock them for independent movement, retaining means to frictionally engage the receiver and hold it at one limit of its play, said retaining means being formed to be loosened from engagement with the receiver by the jarring action of the breech-bolt in its closing movement, and firing mechanism to cause operation of the breech-bolt.

21. A firearm including a frame, a receiver movably mounted on the frame, a lock mounted on one of said members and a controlling slot and retaining recess opening

thereout of and located in the other member in position to receive said lock, said parts being arranged to be moved by the movement of the breech-bolt, a breech-bolt movably mounted in the receiver, and firing mechanism to cause operation of the breech-bolt.

22. A firearm including a frame, a receiver 25 slidably mounted on the frame and having a controlling slot and retaining recess, a lock on the frame located in said slot and in position to enter said recess, a breech-bolt movably mounted in the receiver, said lock being 30 formed to be disengaged by the movement of the breech-bolt, and firing mechanism for causing operation of the breech-bolt.

GRANT HAMMOND.
